Attorney

UNITED STATES PATENT OFFICE

OLIVER H. STOTLER, OF UNIONTOWN, PENNSYLVANIA

SWING HANGER

Application filed May 18, 1932. Serial No. 612,080.

This invention relates to a swing hanger and has for its primary object to provide, in a manner as hereinafter set forth, a device of this character embodying a novel construction, combination and arrangement of parts through the medium of which the relatively movable parts of the hanger will be thoroughly lubricated at all times, thus eliminating squeaks and other annoying noises.

Other objects and advantages of the invention are to provide a swing hanger of the character described which will be simple in construction, strong, durable, efficient and reliable in use, attractive in appearance and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

25 Figure 1 is a view in bottom plan of a swing hanger constructed in accordance with the present invention.

Figure 2 is a view in vertical section through the swing hanger.

30 Referring now to the drawing in detail, it will be seen that the embodiment of the invention which has been illustrated comprises a depending hook 1 which is to be anchored in a swing supporting structure, such as the ceiling of a porch, the upper end portion of the shank of said hook being threaded, as at 2. The hook 1 is engaged in a depending eye screw 3 upon which is mounted a cup 4 for the reception of a lubricant 5.

40 The depending threaded shank 6 of the eye screw 3 extends through the substantially flat bottom of the cup 4 and has fixed thereon in abutting engagement with the inner and outer sides of said cup 4 the comparatively small and large collars or flanges 7 and 8, respectively. The collars or flanges 7 and 8 provide means for rigidly securing the cup 4 in position on the shank 6 of the eye screw 3 and for preventing leakage around said shank 6.

45 50 The lubricant 5 is supplied in the cup 4 in

sufficient quantity to submerge the engaged portions of the hook 1 and the eye screw 3.

55 Mounted on the shank 6 of the eye screw 3 with its bight portion in abutting engagement with the collar or flange 8 is a substantially U-shaped bracket 9 which is secured in position by a nut 10 which is threaded on said shank 6. The nut 10 is preferably square and opposite sides thereof are engaged with the depending legs of the bracket 9 in a manner to prevent rotation of said nut relative to the bracket. A bolt 11 extends between the legs of the bracket 9 for connecting the swing (not shown) to said bracket. The bolt 11 is provided with a retaining nut 12.

60 The reference numeral 13 designates a hood or shield which is mounted on the hook 1 in spaced relation above the cup 4. Nuts 14 are provided on the hook 1 for securing the hood or shield 13 in position thereon. The hood or shield 13 includes a depending skirt portion 15 which extends slightly below the upper portion of the cup 4, as clearly seen in Figure 2 of the drawing. It will also be seen that the hood or shield 13 is spaced sufficiently at all points from the cup 4 to permit swinging movement of said cup in all directions without coming into contact with said hood or shield.

65 70 75 In assembling the hanger, the collar 7 is mounted on the shank 6 of the eye screw 3 after which said shank is inserted through the opening provided therefor in the bottom of the cup 4. The comparatively large collar 8 is then mounted on the shank 6 of the eye screw and engaged with the bottom of the cup 4. Then, the nut 10 is positioned in the bight portion of the substantially U-shaped bracket 9 in alignment with the opening provided in said bight portion for the reception of the shank 6.

80 85 90 95 100 The shank 6 is then inserted through the bight portion of the bracket 9 and threaded through the nut 10. In this manner, the elements 4, 7, 8 and 9 are rigidly clamped together between the nut 10 and the eye of the screw 3. If necessary, any suitable means or composition may be applied for sealing the bottom of the cup to prevent leak-

age but it is thought that this may not be necessary.

It is believed that the many advantages of a swing hanger constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A swing hanger comprising a supporting hook, an eye screw connected with the supporting hook and depending therefrom, a collar mounted on the shank of the eye screw and engaged with the eye thereof, a cup for the reception of a lubricant, mounted on the shank of the eye screw and engaged with the lower side of the collar, another collar mounted on the shank of the eye screw and engaged with the bottom of the cup, a substantially U-shaped bracket mounted on the shank of the eye screw and engaged with the lower side of the second named collar, a nut threadedly mounted on the shank of the eye screw and seated in the bight portion of the bracket, said nut, in conjunction with the eye of the screw, providing means for clamping the collars, the cup and the bracket together on the shank of the eye screw, and means for connecting the bracket to the swing.

35 2. A hanger comprising a supporting member, an eye screw connected to the supporting member, spaced collars mounted on the eye screw, a cup, for the reception of a lubricant, mounted on the eye screw between the collars, a substantially U-shaped bracket mounted on the eye screw, and a nut threadedly mounted on the eye screw and engaged with the bight portion of the bracket, the legs of said bracket being engaged with 45 opposite sides of the nut.

In testimony whereof I affix my signature.
OLIVER H. STOTLER.
